US00D999196S

(12) **United States Design Patent** (10) **Patent No.:** **US D999,196 S**
(45) **Date of Patent:** ** *Sep. 19, 2023

(54) **MICROPHONE AND ADAPTER SET**

(71) Applicant: **Shenzhen Donghuaxiang Technology Co., Ltd**, Guandong (CN)

(72) Inventor: **Yuanfang Cui**, Shenzhen (CN)

(73) Assignee: **Shenzhen Donghuaxiang Technology Co., Ltd.**, Shenzhen (CN)

(*) Notice: This patent is subject to a terminal disclaimer.

(**) Term: **15 Years**

(21) Appl. No.: **29/804,530**

(22) Filed: **Aug. 20, 2021**

(51) LOC (14) Cl. **14-01**

(52) U.S. Cl.

USPC **D14/225**; D14/226

CLAIM

The ornamental design for a microphone and adapter set, as shown and described.

DESCRIPTION

FIG. 1 is a front perspective view of a microphone and adapter set showing my new design;

FIG. 2 is a back perspective view thereof;

FIG. 3 is a front view of the microphone of the microphone and adapter set thereof, shown separately for ease of illustration;

FIG. 4 is a back view thereof;

FIG. 5 is a right side view thereof;

FIG. 6 is a left side view thereof;

FIG. 7 is a top view thereof;

FIG. 8 is a bottom view thereof;

FIG. 9 is a bottom perspective view thereof;

FIG. 10 is a back perspective view thereof;

FIG. 11 is a front view of the adapter of the microphone and adapter set thereof; shown separately for ease of illustration;

FIG. 12 is a back view thereof;

FIG. 13 is a right side view thereof;

FIG. 14 is a left side view thereof;

FIG. 15 is a top view thereof;

FIG. 16 is a bottom view thereof;

FIG. 17 is a front perspective view thereof; and,

FIG. 18 is a back perspective view thereof.
